Primary Examiner — Brian N Vinson(74) *Attorney, Agent, or Firm* — Craig M. Stainbrook; Stainbrook & Stainbrook, LLP(57) **CLAIM**

The ornamental design for a grow light reflector, as shown and described.

DESCRIPTION

FIG. 1 is a lower right rear perspective view, dashed lines indicate unclaimed elements;

FIG. 2 is an upper left front perspective view, dashed lines indicate unclaimed elements;

FIG. 3 is a front elevational view, the rear elevational is a mirror image thereof, dashed lines indicate unclaimed elements;

FIG. 4 is a right side elevational view, dashed lines indicate unclaimed elements;

FIG. 5 is a bottom plan view, dashed lines indicate unclaimed elements;

FIG. 6 is a top plan view, dashed lines indicate unclaimed elements;

FIG. 7 is a left side elevational view, dashed lines indicate unclaimed elements; and,

FIG. 8 is a cross sectional view along line 8-8 in FIG. 5, dashed lines indicate unclaimed elements.

The broken lines shown in the drawings are included for purposes of illustrating environmental structures only and form no part of the claimed design.
